UNITED STATES PATENT OFFICE

122,297

DESIGN FOR A FINGER RING OR SIMILAR ARTICLE

John J. Klecka, Mount Vernon, N. Y., assignor to J. R. Wood & Sons, Incorporated, New York, N. Y., a corporation of New York

Application July 5, 1940, Serial No. 93,456

Term of patent 14 years

To all whom it may concern:

Be it known that I, John J. Klecka, a citizen of the United States of America, residing at 19 William Street, Mount Vernon, New York, have invented a new, original, and ornamental Design for a Finger Ring or Similar Article, of which the following is a specification, reference being had to the accompanying drawing, forming part thereof.

Fig. 1 is a perspective view of a finger ring or similar article showing my new design;

Fig. 2 is a developed plan view of a finger ring showing my new design.

The essential features of my design reside in the fillet on the outer periphery of the ring band. While I have shown my design in the form of a finger ring, it is understood that the same may be embodied in other similar articles of jewelry.

I claim:

The ornamental design for a finger ring or similar article, as shown and described.

JOHN J. KLECKA.
